[57] CLAIM

The ornamental design for a physical exerciser, as shown and described.

DESCRIPTION

FIG. 1 is a front perspective view of a insert title as amended showing my new design;

FIG. 2 front perspect view thereof showing the seat member in an alternate condition;

FIG. 3 is another front perspective view thereof showing the seat member in an upright condition;

FIG. 4 is a bottom perspective of the design as position in FIG. 1; and,

FIG. 5 is another front perspective view thereof with the seat in an alternate condition.

The texture shown in fragment in the drawings represents an overall texture within the areas indicated.

FIG. 1

FIG. 2

FIG. 3
